CLAIM

The ornamental design for a smoking pipe with swivel stem, or similar article as shown and described.

DESCRIPTION

Fig.2.

Fig.3.
